UNITED STATES PATENT OFFICE.

RALPH E. HART, OF FORT WAYNE, INDIANA.

DESIGN FOR A SELF-HEATING SAD-IRON.

47,820.

Specification for Design.

Patented Sept. 14, 1915.

Application filed June 17, 1915. Serial No. 34,747. Term of patent 14 years.

To all whom it may concern:

Be it known that I, RALPH E. HART, a citizen of the United States, residing at Fort Wayne, in the county of Allen and State of Indiana, have invented a new, original, and ornamental Design for a Self-Heating Sad-Iron, of which the following is a specification, reference being had to the accompanying drawing, forming a part thereof.

The figure is a perspective view of a self-heating sad-iron, showing my new design.

I claim:

The ornamental design for a self-heating sad-iron, as shown.

RALPH E. HART.
